CARTON CLOSING AND PRINTING DEVICE
FOR CARTONING MACHINESJohn F. Currihan, Dayton, Ohio, assignor, by
mesne assignments to Emhart Manufacturing
Company, a corporation of Delaware

Application January 12, 1949, Serial No. 70,454

21 Claims. (Cl. 53—60)

1

This invention relates to cartoning machines or the like, and in particular to devices thereon for finally closing the end flaps thereon and printing on the cartons before they are discharged from the cartoning machine.

The invention is particularly adapted as an improvement in cartoning machines of the type shown in the United States application of Alexander H. Ross, Serial No. 731,395, filed February 27, 1947, and entitled "Cartoning Machine." In machines of that type, flattened cartons are fed from a magazine onto a "transport" conveyor where they are erected to rectangular shape, loaded with an article of merchandise, and one or both of their ends closed. On the "transport" the cartons are moved in a direction transverse to their end openings and the movement is smooth and continuous. They are spaced one from the other along their path of travel, and are moved along that path by "fingers" that protrude through the supporting surface of the transport, so that until the cartons have been discharged at the end of the transport they are moved there along at a constant speed.

One of the last operations upon the cartons before their discharge is the final closing of the top or end flaps, which top or end flaps, if not secured in place by adhesives, generally have tuck flaps at their free ends. These tuck flaps are slipped into the ends of the carton and retain the top flaps closed after they have once been pushed to fully closed position. Fixed devices in the path of movement of the top flaps and attached tuck flaps first crease the tuck flaps with respect to the top flaps and then turn the latter towards closed position while guiding and inserting the tuck flaps into the carton ends. As disclosed in the aforesaid application Serial No. 731,395 after the cartons have passed the tuck flaps creasing and inserting assemblies the top flaps are not fully closed against the ends of the cartons and the tuck flaps are not fully inserted, and final closing is accomplished by pairs of freely rotating rollers adjacent the paths of the ends of the cartons, which rollers successively engage the top flaps of the moving cartons and press them to fully closed position.

The freely rotating closing rollers perform their intended function satisfactorily when the cartons are fabricated of relatively heavyweight cardboard. However, cartons formed of lightweight or thin cardboard react differently to the tuck flap creasing and inserting assemblies and are frequently pulled out of their rectangular configuration. This out of square condition is fur-

ther aggravated upon contact of the top flaps with the free closing rollers and there results a mutilation of the trailing edge of the tuck so that the trailing edge of the top flap is left overhanging the trailing side wall of the carton.

I have overcome this difficulty by the provision of power driven closing devices which in the illustrated examples comprise rollers or chains that are driven at a rate faster than the movement of the cartons along the transport, so that there results a wiping engagement between the rollers or chains and the top flaps or the cartons. This wiping engagement not only completes the closing of the top flap over the end of the carton, but if the carton has been deformed into an out of square condition during the tuck flap creasing and inserting operation the carton is returned to its normal intended shape.

It is frequently desirable to print certain information upon the ends of the cartons. Examples of such information are the date of expiration of photographic film, or the batch or lot number of some particular product, etc. Since it is desirable to print this information after the articles have been cartoned it is particularly convenient to do so after the carton has been completely closed and before it is discharged from the cartoning machine. I have devised printing means which are combined with the final top flap closing devices. Since successful printing is dependent upon proper carton configuration and correctly closed top flaps, I have also combined the printing means with the power driven closing devices, in order to assure that even in the case of thin walled cardboard cartons the top flaps will be correctly closed and the cartons properly formed to facilitate the printing.

It is accordingly the primary object of my invention to provide improved closing means for carton flaps whereby the top and tuck flaps are accurately and fully closed.

Another important object of my invention is the provision of combined carton closing and printing means.

It is another important object to provide an improved carton flap closing means which will not deform fragile cartons and which will restore proper configuration to deformed cartons.

Another important object is the provision of a power driven closing device for carton flaps combined with printing means for printing upon the flaps after they are closed.

It is another important object to provide improved flap closing devices for cartons wherein the closing devices have a movement in the same

direction as the cartons but at a faster rate whereby a wiping action between the flaps and closing devices results in accurate closing of the flaps.

Other objects will become apparent as the description proceeds in connection with the accompanying drawings, wherein:

Figure 1 is a perspective view of one form of my carton closing device.

Figure 2 is a top plan view of another embodiment of the device shown in Figure 1.

Figure 3 is a side elevation of one of the closing assemblies of Figure 2, as viewed substantially along the line 3—3 of Figure 2.

Figure 4 is a side elevation of the assembly shown in Figure 3, as viewed from the right thereof.

Figure 5 is a top plan view of another embodiment of final closing device.

Figure 5a is an enlarged sectional view along line 5a—5a of Figure 5.

Figure 6 is a side elevation of Figure 5, as viewed from the top of Figure 5.

Figure 7 is an enlarged partial sectional view along the line 7—7 of Figure 5, with portions behind the section line omitted for the sake of clarity.

Figures 8 and 9 are top plan and side elevation views of one form of final closing device combined with a printer, and Figure 10 is a partial sectional view along the line 10—10 of Figure 8; and

Figures 11 and 12 are top plan and side elevation views of another form of final closing device combined with a printer.

In Figure 1 is shown a portion of a cartoning machine of the type shown in the aforesaid application Serial No. 731,395. A transport base or frame 15 mounts a pair of spaced longitudinally extending table plates 16 and 17 which form a planar surface along which the cartons 18 are moved from right to left as viewed in Figure 1. The cartons are moved along at a constant speed by fingers which project upwardly through the space between the table plates. The rear or trailing wall of each carton is engaged by a pair of transversely spaced fingers 19 and 20, and in Figure 1 one of these pairs is shown beginning to disappear beneath the table plates as the chains which carry them round the sprockets on the headshaft which is not shown in Figure 1 but which is mounted within the base 15 and is motor driven to drive the cartoning machine. A hand-wheel 21 is mounted on the headshaft for free rotation with respect thereto, but may be positively connected thereto for the purpose of driving the machine by hand during adjustments, etc. Although it may be said that the cartons are pushed along the plates 16 and 17 by the pairs of trailing fingers 19 and 20, they are also confined against these fingers by forward fingers 22 (only one of which appears in Figure 1) which are carried by a central chain 23, also driven by a sprocket on the headshaft. In Figure 1, only one chain 24 which carries the trailing fingers 20 is shown, the other similar chain that carries the opposite fingers 19 being out of sight behind one of the two intermediate surface plates 25 and 26. A hold down bar 27 carried by an overarm 28 holds the cartons against the table plates so that they do not shift with respect to the table plates while they are being loaded with merchandise and their flaps are folded and closed by plows and other devices carried by the compounds 29, 30, and 31 and by the overarm 28, 75

etc. As described in the aforesaid application Serial Number 731,395, the compounds 29, 30 and 31, and the overarm 28 are adjustable, and the longitudinal distance between the leading fingers 5 22 and the trailing fingers 19 and 20 is adjustable so that the cartoning machine can handle cartons of various sizes within the range of adjustments. For that reason my improved final closing devices and the printing means are also adjustable to accommodate cartons within the same range of sizes.

Referring still to Figure 1, five of the cartons 18 are visible to the left of the overarm 28 and it can be seen that the two cartons closest to the overarm have their tuck flaps 32 creased with respect to the top flaps 33, and the tuck flaps are only partially inserted into the end of the carton. A similar condition exists with respect to the top and tuck flaps on the other ends of the cartons, although as will be apparent from the rightmost cartons in Figure 1, the top flaps 33 are bent downwardly and the tuck flaps 32 are inserted adjacent the bottom carton walls, since the illustrated cartons are of the "reverse tuck" type.

It is the function of my improved closing device to fully press the two top flaps against the ends of the carton, thus closing them completely and forcing the tuck flaps completely into the carton, without deforming the flaps or cartons, and in fact restoring them to proper configuration if they have been deformed during prior operations. As previously mentioned, the device may also include a printer for printing upon the completely closed top flaps.

Referring still to Figure 1 which illustrates one form of my invention, a mounting plate 36 is secured to the horizontal leg of an angle member 37, which is in turn mounted upon the face plate 38 of a compound 39. The details of construction of the compound 39, and of the other compounds shown, are not repeated here since they are fully described in the aforesaid copending application Serial No. 731,395. It is sufficient to state here that compound 39 is supported by a bracket 40 suitably affixed to the outer side wall of the base 15 and that the movable parts of the compound, including its face plate 38 are adjusted horizontally and perpendicularly towards or away from the center of the machine by turning the thumb screw 41. This moves the mounting plate 36 and all of the elements carried thereby, to proper position depending upon the size of cartons being handled, and the compound is fixed in adjusted position by tightening a locknut 42 adjacent the thumb screw 41.

A pair of ball bearing assembly housings 43 and 44 secured to the plate 36 mount shafts 45 and 46 respectively for rotation about vertical axes, shaft 46 being spaced slightly further from the center of the machine than shaft 45. Each shaft has a drum fixedly mounted thereon for rotation therewith, identified by the reference numbers 47 and 48, the surfaces of the drums being covered with rubber, which may be in the form of bands, and which provide frictional engagement with the top flaps of the cartons. Details of construction of the drive for the drums 47 and 48 of Figure 1 are shown in Figures 2 to 4 and for that reason are not shown on Figure 1, being out of sight under the protective cover 49 affixed to the movable compound 39. Visible however in Figure 1 is a sprocket chain 50 that is trained over sprockets on shafts 45 and 46, over a tension adjustment sprocket and also over 70 a drive sprocket that is driven from the trans-

port head shaft as shown in detail in Figures 2 to 4. The shafts 45 and 46 are driven clockwise as viewed in Figure 1 and at such a rate that the peripheral speed of the drums 47 and 48 is greater than the rectilinear speed of the cartons 18 on the transport, the result being that the rubber coverings on the drums exert a wiping action on the top flaps of the cartons, in the direction that the cartons are moving while at the same time drum 48 pushes the top flap slightly further towards closed position and then drum 47 closes it still further.

Attached to the bottom of mounting plate 36 by screws 51 passing through slots in the mounting plate is a vertical plate 54 that extends downwardly and preferably rests upon the table plate 16 to give additional support to the mounting plate. The vertical plate 54 may be adjusted to be parallel to the movement of the cartons so as to merely hold the top flaps closed, or it may be inclined with respect to their path of movement so as to complete the closing operation, this adjustment being made by the screws 51 and their slots. Also, the position of the mounting plate 36 may be adjusted in the horizontal plane by reason of the screws 55 passing through slots in the mounting plate and securing it to angle member 37. This permits rotating the mounting plate slightly to adjust the relative positions of the rotating drums 47 and 48 with respect to the ends of the cartons. These adjustments are important, because depending upon the dimensions of the cartons and the material of which they are made, adjustments of the drums and of the plate 54 are needed to fit the particular situation, in addition to the adjustment for carton length provided by the adjustable compound 39. Another vertical plate 56 may be secured to the mounting plate 36 in such position as to hold the top flaps of the cartons closed to the extent that they have been closed by the drum 48 and before they are further closed by drum 47.

On the other side of the transport another adjustable compound 57 mounts an assembly that is identical with the one just described and has closing drums mounted on power driven shafts 58 and 59 directly across the transport from the shafts 45 and 46. They are driven from the transport head shaft in the same manner as shafts 45 and 46, by another power take off of the type shown in Figure 4 but mounted upon the right side of the transport base 15 of Figure 1, the mechanism being out of sight under the cover guard 60.

Figures 2 to 4 show another embodiment similar in most respects to the left hand closing assembly of Figure 1, but wherein the two assemblies on the opposite sides of the transport are identical, so that only one single power take off shaft 61 (Figure 4) extending transversely through the transport base and protruding through its opposite side walls 62 and 63 will drive both assemblies through bevel gears as shown at 64 and 65 in Figure 4. A sprocket 66 is keyed to the power take off shaft 61 and is driven from the transport head shaft by a sprocket chain 67.

Since the assemblies on the opposite sides of the transport are identical, and identified generally of the reference numbers 68 and 69 the description will be confined to the upper assembly 68 in Figure 2, which is also shown in side and end elevations in Figures 3 and 4.

The adjustable compound 70 is secured to the 75 transport base 15 by the bracket 71 and an angular member having a horizontal leg 72 is fixedly secured to the face plate 73 of the compound.

5 A mounting plate 77 is adjustably secured in a horizontal plane to the leg 72 by the screws 74 passing through slots in the plate. A pair of shafts 75 and 76 are mounted upon the plate 77 for rotation about vertical axes, by means of ball bearing assemblies held within housings 78 and 79 that are affixed to the plate 77. Figure 3 shows for shaft 76, how each shaft has a reduced upper end providing a shoulder abutting the bearing inner race, the shaft being held within the race by a screw 80 and washer 81. Shafts 15 75 and 76 have keyed thereto the drums 82 and 83 each of which is covered with a frictional surface as for example the rubber bands 84. The shafts 75 and 76 also have affixed thereto, as by set screws, the chain sprockets 85 and 86 respectively. As in Figure 1, the peripheral surface of the drum 83 is slightly farther from the ends of the cartons than the surface of drum 82, so that drum 82 will close the top flaps further than drum 83.

20 25 The bevel gears 64 and 65 (Fig. 4) are in a housing 87 that is secured to the transport base side wall 62 by means of screws 88, and a bearing housing 89 secured to the housing 87 mounts a pair of bearing assemblies that journal a shaft 90 for rotation about a vertical axis, the shaft 90 having the bevel gear 65 keyed thereto. At its upper end the vertical shaft 90 has keyed thereto a chain sprocket 91 around which is trained a sprocket chain 92 which also passes around the sprockets 85 and 86 on shafts 75 and 76, as well as about a tensioning sprocket 93 mounted upon a vertical spindle 94 that is adjustably secured to the top of the side wall 62 of the transport base by a screw 95 which passes through a slot 96 in a horizontal plate 97 to which the spindle is secured as by welding.

but the back up plate 98 preferably rests upon the table plate, thus giving additional support to the mounting plate 77 without interfering with the transverse adjustment provided by the compound 70. As in the embodiment of Figure 1, the amount of closing accomplished by each of the drums 82 and 83, by the back up plate 98 and by the roller 106 can be adjusted by reason of the slots through which pass the screws 14, 100, and the stud shaft 107, it being understood that cartons of various sizes and materials will generally require independent adjustment of these elements, and that another factor is whether the top flaps are hinged to the bottom wall of the carton or to the top wall thereof.

A cover guard 112 covers the sprockets 91 and 93 and most of the chain 92, being fastened to the mounting plate 77 as by screws 113. As in the embodiment of Figure 1, the power driven drums 82 and 83 have a faster peripheral speed than the linear speed of the cartons 18, so that they will effect a wiping action on the carton top flaps. The back up plate 98 has its forward edge 114 (Figs. 2 and 3) closely adjacent the periphery of drum 82 and sufficiently behind it so that the carton top flap leaving the drum 82 will not get caught on the back up plate. Another back up plate 115 (Fig. 2) is secured to the mounting plate 77 between the drums 82 and 83 by a screw 116 to prevent the opening of the top flap after leaving drum 83. This plate 115 is omitted in Figure 3 in order to more fully expose the drums and chain, etc. to view. As shown in Figure 4, a graduated scale 117 on the movable compound cooperates with a fixed index mark 118 on the bracket 71 so that settings of the compound and the assembly carried thereby can be recorded for future reference when resetting the compound again for cartons of that same size.

Figures 5, 6 and 7 illustrate another embodiment of my invention wherein power driven converging platform chains engage the top flaps of the cartons to close them fully and to return the carton ends to correct rectangular configuration if they have been deformed by previous tucking or creasing operations, etc.

Referring to the upper assembly 121 in the plan view of Figure 5, a generally triangular mounting plate 124 is pivotally mounted upon the compound 125 by a screw 126 threaded into the plate and passing through the horizontal leg 127 of an angle bracket secured to the face plate 128 of the compound 125, the mounting plate lying against the lower surface of the said horizontal leg, and having a transverse through slot 129 so as to enable it to clear the compound 125 and its supporting bracket 123 (Fig. 6). Two other screws 130 and 131 passing through arcuate slots 132 and 133 in the said horizontal leg and threaded into the mounting plate secure the mounting plate in any selected angular position around the pivot screw 126.

As shown in Figs. 5, 5a, 6 and 7, each of the shafts 136, 137 and 138 carries two chain sprockets, all of the lower sprockets lying in the same horizontal plane and having a driving sprocket chain 139 (Fig. 6) trained over them. Similarly all of the upper sprockets lie in the same plane and have a carton engaging sprocket chain 140 (Figs. 5 and 6) trained over them, this last chain being of the platform type, wherein each link has an elongated face plate 141 (Figs. 5 and 6) integrally mounted thereon. The face plates 141 are in a vertical plane and their adjacent vertical edges are in substantially abutting

relationship when the chain 140 is traveling in a rectilinear path. Thus each of the chains 139 and 140 each follows a substantially triangular path. However in order to back up the carton 5 engaging sprocket chain 140 while it is engaging the cartons between shafts 137 and 138 a horizontally extending track 142 (Fig. 5) engages the chain rollers. The track 142 is welded or otherwise secured to a horizontal bar 143 that is suitably affixed by welding or the like to the bottom surface of the mounting plate 124. If desired, the lower sprocket chain 139 may be trained over a track similar to track 142 and secured to the bar 143 below and in parallel arrangement 10 with respect to track 142.

Referring to Figure 7, a shaft 144 is mounted in a bearing housing attached to the transport base side wall 62 by screws 145, and it is driven from the transport head shaft 135 (Fig. 6) by 20 a chain 146 and sprocket 147, the vertical shaft 136 being in turn driven by the bevel gear set 148. Of the two sprockets 149 and 150 on the shaft 136, only the lower sprocket 149 is fixed or keyed to the shaft, so that it thereby drives the lower 25 sprocket chain 139. The upper sprocket 150 rests upon the top of sprocket 149 and is free to rotate on shaft 136, although as will be apparent, it will rotate at the same speed as sprocket 149 by reason of the fact that the upper sprocket chain 30 140 is trained over the sprocket 150.

Referring to Figure 5a the shaft 137 has a lower head 151 which retains a lower sprocket 152 and an upper sprocket 153 that are journaled for free rotation on oil impregnated bushings 154 and 155, the combined axial length of these bushings being slightly greater than the combined axial length of the two sprockets. A spacer washer 156 overlies the upper bushing and the upper threaded end of the shaft 137 protrudes 40 through the mounting plate 124 so that an acorn nut 157 can draw the shaft 137 up tightly and secure it to the mounting plate while the sprockets 152 and 153 are free to rotate upon the bushings 154 and 155. The lower sprocket chain 139 passes around sprocket 152 and the upper sprocket chain 140 passes around sprocket 153.

The third pair of sprockets 160 and 161 (Fig. 6) are journaled for rotation about the shaft 138 which has a single oil impregnated bushing 162 confined between a spacing washer 163 and an enlarged head 164 on the lower end of the shaft. The upper end of the shaft 138 protrudes through an elongated slot 165 (Fig. 5) in the mounting plate 124, which slot is narrower than the diameter of the shaft. The shaft is flattened on two 50 diametrically opposite sides so that it protrudes through the slot and can slide the length of the slot but cannot rotate therein. A member which is U shaped, having upper and lower legs 166 and 167, connected by a yoke 168 embraces the mounting plate 124 as best shown in Fig. 6, and has axially aligned holes through its legs having the same shape as the flattened upper end of the shaft 138, which protrudes through the legs 166 and 167 as well as the mounting plate 124. A shoulder 169 is formed on each side of the shaft 138 at the lower end of each flattened portion, and these shoulders limit the upward movement of the shaft through the leg 167. A knurled nut 170 is threaded onto the threaded upper end of the shaft 138, and when tightened the shaft is fixed in any selected position along the slot 165 because the mounting plate 124 and the legs 166 and 167 are clamped between the nut 170 and the shoulders 169 on the shaft. Thus this ar-

angement provides an adjustment for the tension of the chains 139 and 140 which pass around the sprockets 160 and 161 respectively. A bolt 171 having a knurled head 172 is threaded through the connecting yoke 163 and its end engages the edge of the mounting plate so that after the nut 170 is loosened, the shaft 138 can be pulled along the slot 165 by turning the bolt 171, thus tightening the chains 139 and 140 to the proper tension, after which shaft 138 can be locked in place by tightening the nut 170. The sprockets 160 and 161 are free to rotate about the bushing after shaft 138 is clamped in place. Instead of being freely rotatable with respect to each other as are the pairs of sprockets on shafts 136 and 137, the two sprockets 160 and 161 are rigidly secured together as by welding or the like. Thus the driving effort of the shaft 136 is transmitted through the chain 139 to the sprockets 160 and 161 of shaft 138, so that as viewed in Figure 5 where the chains are moving from left to right along the track 142 there will not be any slack in the platform carrying chain 140 between shafts 137 and 138.

In operation, the mounting plate 124 is adjusted, by means of the clamping screws 130 and 131, so that the track 142 is closer to the cartons at its left end than at its right end as viewed in Figure 5. The arrangement is such that when the carton top flaps are first engaged by the chain face plates 161 the tuck flaps 32 are only partially inserted into the cartons, but by the time the face plates 161 recede away again from the cartons, indicated by the point identified by reference number 173 in Figure 5, the tuck flaps have been fully inserted and the top flaps pressed flat against the ends of the cartons.

The diameters of the sprocket 167, bevel gears 148, sprocket 149 etc. are such that the upper sprocket chain 140 and the face plates 161 carried thereby move faster than the cartons, so that the face plates effect a wiping action on the carton top flaps in the direction of movement of the cartons, thereby squaring up the cartons and flaps where they have been deformed during the previous creasing and tucking operations. As best shown in Figure 6, the length of the face plates 161 forming the platform surface of the chain 140 are such that they extend almost to the top surface of the transport table plate 16, and also extend an equal distance vertically upwardly above the chain 140.

In this embodiment all of the chains and sprockets etc. are below the mounting plate 124 which thereby provides a partial guard for the operator. For further protection a pair of downwardly depending skirts 175 and 176 (Figs. 5 and 6) and secured to the edge of the mounting plate 124.

The assembly 122 on the other side of the machine (Fig. 5) for fully closing the other ends of the cartons may be of identical construction to the assembly 121 just described, and symmetrically arranged upon the other side, as will be understood. However, since there is more room on the other side, due principally to the absence of a handwheel 21 on that side, the assembly 122 may be slightly modified to reduce the number of parts, in the manner shown in Figure 5.

The vertical shaft 179 that powers the assembly 122 is arranged in the same vertical plane as the transport head shaft 135, which is extended through the side wall of the transport base and provided with a bevel gear to drive a mating bevel gear on the vertical shaft 179 in a manner similar

to that shown in Figure 7, the shaft 179 being driven in a counter-clockwise manner. The other two shafts 180 and 181 that are carried by the mounting plate 182 are directly laterally opposite to the shafts 138 and 137 respectively of the opposite assembly 121 so that the carton engaging platform type sprocket chain 183 will be directly laterally opposed to the corresponding chain 140 of the assembly 121.

10 Due to the fact that the vertical drive shaft 179 is closer to the adjustable shaft 180 than is the case in the assembly 121, it is possible to drive the platform chain 183 directly by the sprocket 184 on the shaft 179, so that no driving sprocket 15 chain corresponding to the lower chain 139 of assembly 121 need be used, and no lower sprockets corresponding to sprockets 149, 160 and 152 of assembly 121 are required. The single sprockets 185 and 186 on shafts 180 and 181 respectively are thus merely idling and chain supporting and guiding sprockets to train the chain 183 over the track 187 which is directly laterally opposite to the track 142. Chain 183 moves at the same speed as chain 140.

15 In the embodiment of Figures 8 to 10 the final closing device is combined with a mechanism which prints upon the top flap on one end of the carton after it has been fully closed so as to have support while the printing impression is made.

20 The compound 188 is adjustable as are all the others shown in this application, and described in detail in the aforesaid application Serial No. 731,395. Its mounting bracket 189 fits over a dovetail slide 190 that is rigidly secured to the 25 side wall 62, and a gib 191 engages the under side of the slide and clamps the bracket 189 against the slide by means of screws 192. This permits longitudinal adjustment of the compound 188 and the assembly carried thereby, lengthwise along the transport base. It should be understood that the device shown in Figures 8 to 10 is operative only upon the top flaps on one side of the carton, and that final closing devices of some type, such as any of those described in this application must 30 be used to close the top flaps on the other side of the transport, or if the top flaps have already been closed on the other side, there must be a back up bar on that other side, to keep the cartons from sliding transversely of the transport 35 due to the forces exerted by the combined closing and printing assembly of Figures 8 to 10. This assembly shown in Figures 8 to 10 is advantageously substituted for the assemblies carried by the compound 39 of Figure 1, 70 of Figure 2, 40 or 125 of Figure 5. Also, if printing is desired on 45 both ends of the carton an assembly similar to that of Figures 8 to 10 can be used on the other side of the machine.

50 An angled member has its vertical leg 193 (Fig. 60 10) fastened to the face plate 194 of the compound in any suitable manner. The horizontal leg 195 is bored for the passage of a bolt 196 having an integral knurled head 197, the bolt passing through a spacer bar 198 underlying the horizontal leg 195, and being threaded through a horizontal mounting plate 199, whereby tightening of the bolt 196 will secure the mounting plate to the angled member and to the compound 188 for adjustment towards or away from the cartons. A horizontal bar 200 is affixed to the vertical leg 193 in the same plane as the mounting plate 199. Bolts 201 and 202 are threaded through the bar 200 adjacent its ends, as best shown in Figure 8, the threaded ends of the bolts 55 engaging the vertical edge of the mounting plate

whereby they may be turned in one direction or the other to adjust the position of the mounting plate about the bolt 196, and to lock it there. Lock nuts 203 on the bolts 201 and 202 secure them against loosening after they have been adjusted.

The right end of the mounting plate 199, as viewed in Figures 8 and 9, is rigidly supported by a bolt 204 passing through an arcuate slot 205 in the mounting plate, through a supporting post 206, and threaded into the table plate 16. A pair of rollers 207 and 208 similar to the roller 106 of Figures 2 to 4 are carried by bearing assemblies mounted on a horizontal bar 209 which is adjustably secured to the under side of the mounting plate 199 by a bolt 210 passing through a slot 211 in the mounting plate and threaded into the said bar 209. The bolt has an integral knurled head 212, and the bar 209 may be moved towards or away from the cartons and rotated about the axis of bolt 210 to adjust the position of the rollers with respect to the moving cartons. This arrangement is similar to the adjustment for the final closing rollers shown and described in the aforesaid application Serial Number 731,395. A vertical plate 213 is suitably secured to the under side of the mounting plate 199, extending downwardly and resting upon the table plate 16, its purpose being to hold the top flaps of the cartons in the position that they left the last preceding tuck creasing or inserting apparatus, so that the partially inserted tuck flaps will not slip out of the cartons before they are engaged by the first roller 207.

At 217 is shown a rotatable drum of conventional construction, having peripheral grooves for holding removable type. The drum is mounted for rotation about a vertical axis by means of a shaft 218 suitably fixed in the inner race of a ball bearing assembly 219 that is secured to the under side of the mounting plate 199, the shaft 218 protruding through the top of the mounting plate and having a chain sprocket 220 keyed to its upper end. A driving sprocket 221 is keyed to a vertical shaft 222 that is mounted and driven from the transport headshaft in the same manner as shaft 136 in Figures 6 and 7. The sprocket 221 drives the sprocket 220 by a sprocket chain 223 at such a speed that the speed of the type 224 mounted in a groove in the drum is the same as the rectilinear speed of the cartons so that there will be no slippage between the type and the carton top flaps while the printing is being made thereon. Only one group of type elements 224 is shown in Figure 8, but the number will depend upon the drum diameter and distance between cartons, as will be understood. Slack in the chain 223 is taken up by an idler sprocket 225 on a shaft 226 carried by an arm 227 adjustably mounted on a pivot post 228 that is threaded into the compound 188 and further supported by a bracket 229. The arm 227 is secured in any selected position by a headed screw 230 passing through a slot 231 in the arm 227 and threaded into the bracket 229.

Ink for the type elements 224 is supplied by a rubber inking roller 232 freely rotatable upon a vertical shaft passing through and secured to the mounting plate 199 by an acorn nut 233, the surface of the inking roller being so arranged with respect to the drum 217 that the rotating type elements contact its surface and transfer sufficient ink from the roller to themselves once for each revolution of the drum 217. The inking

roller 232 has a flange 234 which is engaged by the top flange 244 on the drum 217 to drive the inking roller at the same peripheral speed as the drum 217.

5 The rubber inking roller also contacts and rotates a felt roller 235 freely rotatable upon a shaft 236 secured to the mounting place 199 by an acorn nut 237 (Fig. 10). An ink reservoir is provided by a conventional adjustable drip type oil cup 238 secured to the mounting plate 199 and having a discharge tube 239 (Fig. 10) terminating just above the edge portion of the felt roller 235, so that the ink dripping from the supply in the cup 238 at a controlled rate will fall upon and soak into the felt roller.

A vertical backing plate 241 is fixedly secured to or integral with the mounting plate 199 and depends downwardly therefrom into close proximity or engagement with the top surface of the table plate 16. Its function is to hold the top flap closed after it has passed the final closing roller 208, and it extends from a point adjacent the roller 209 to the right end of the mounting plate. However, in order to permit the type 224 to print upon the carton ends the backing plate is milled or otherwise cut away as indicated by the edges at 242 and 243 in Figures 8 and 9, this also preventing interference between the top flange 244 of the drum 217 and the back up plate, since as viewed in Figure 8 the flange would rub against the plate. Some of the cartons handled by the machine are such short height that they might strike against the second edge 243 in the back up plate 241. To prevent that, a bridge member 245 is set into the face of the back up plate 241, so that it is flush with its working face, and bridges the milled out portion between the plane of the drum flange 244 and the plane of the type elements 224. Also, to the right of the second edge 243 the working face of the back up plate 241 is milled out slightly to provide a depression indicated by the dotted lines 246 and 247 in Figure 9, so that the ink deposited on the carton top flap by the type 224 will not smear against the back up plate. In order to provide a gradual release of the top flap by the back up plate as the carton nears the end of the transport, a horizontal slot 248 (Fig. 9) is cut in the back up plate, and the portion 249 below the slot is bent gradually away from the general plane of the back up plate as best shown in Figure 8. This embodiment, wherein the final closing rollers 207 and 208 are not power driven, is suitable where the cardboard forming the carton is sufficiently stiff so that the carton is not deformed by the previous operations, and so that the carton tuck and top flaps will not be deformed when engaging the freely rotatable final closing rollers.

In the embodiment of Figures 11 and 12 the printing device is combined with power driven closing rollers of the type shown in Figure 2, so that all types of cartons having different degrees of rigidity, etc. can be handled with the assurance that there will be no mutilation of the top flap and that the printing will be placed squarely upon the top flap of the closed carton.

The adjustable compound 251 is affixed to the side wall 63 of the transport base by a bracket 252, the entire assembly about to be described being capable of substitution for the assembly 69 of Figure 2 or 122 of Figure 5, since the cartons 18 of Figure 11 are moving from left to right.

An angle member having its vertical leg 253

affixed to the face plate 254 of the compound as by screws 255, has a horizontal leg 256 extending toward the cartons 18 and forming a support for a mounting plate 257, which rests upon it and is adjustably secured thereto by screws 258 passing through slots 259 in the mounting plate and threaded into the horizontal leg. Closing drums 261 and 262 similar to the drums 82 and 83 of Figures 2 to 4 are mounted for rotation by bearing assemblies 263 and 264 fixed to the mounting plate 257. In order to bring the frictional coverings 265 and 266 on the closing drums as close as possible to the top surface of the table plate 17 and thus engage as much of the carton top flaps as possible, the table plate may have a longitudinal recess 267 and the bottom ends of the drums can project down into the recess. The shafts 269 and 270 of the closing drums have sprockets 271 and 272 respectively keyed to them. A printing drum 275 similar to the drum 217 of Figures 8 to 10 is rotatably mounted upon the mounting plate by a bearing assembly 276 and the drum shaft 277 has keyed thereto a sprocket 278. The type held by the printing drum is inked by a rubber roller 279 (Figure 11), which is in turn inked by a felt roller 280 and an ink reservoir 281, all in the same manner as described in connection with Figures 8 to 10. The rollers 279 and 280 and the reservoir are carried by the mounting plate 257.

A vertical shaft 282 mounted in a housing 283 attached to the side wall 83 is driven counter-clockwise by a connection to the transport head shaft, in the same manner as shaft 136 of Figures 6 and 7, and it has keyed thereto a sprocket 284. A sprocket chain 285 is trained around sprockets 271, 272, 278 and the driving sprocket 284 as well as around idler sprockets 286 and 287, and the relative diameters of the sprockets are such that the peripheral speed of the frictional coverings on drums 261 and 262 is greater than the linear speed of the cartons 18, while the peripheral speed of the type in the printing drum 275 is the same as that of the cartons. The idler sprocket 286 is freely rotatable on a shaft 288 (Fig. 11) threaded into the horizontal leg 256 of the angle member, and its function is to guide the chain 285 around the bracket 252, which is also slightly cut away at 289 to provide clearance for the chain. The other idler sprocket 287 is for the purpose of adjusting the chain tension, and it is freely rotatable on a shaft 290 affixed to a horizontal plate 291 adjustably positioned on top of the cartoning machine base by a screw 292 threaded into the base and passing through an elongated slot 293 in the plate 291. This provides means for adjusting the chain tension, as is required when the assembly is shifted laterally to accommodate cartons of various sizes within the range of the cartoning machine, since the shaft 282 and sprocket 284 remain fixed during such adjustments.

A vertical back up plate 294 is adjustably mounted upon the mounting plate 257, being secured by screws 295 to a block 296 which is adjustably secured to the mounting plate by screws 297 passing through slots in the mounting plate. The back up plate holds the carton flaps closed after they pass drum 262. At its lower edge the back up plate rests upon the table plate 17 within the recess 267. The back up plate 294 has a window 298 through which the type on the printing drum 275 projects to print

upon the carton flaps, and to the right of the window the face of the back up plate has a recess 299 in its working face so that the ink on the flap will not be smeared.

I have thus provided improved devices for fully closing the top flaps, fully inserting the tuck flaps and printing on continuously moving cartons, in such manner that the cartons are squared if previously deformed, and so that the top flaps lie flat against the carton ends to assure accuracy of the printing.

While my improved closing devices have been described specifically in connection with the final closing of cartons having tuck flaps, it is to be understood that they are equally operable upon cartons having other types of end or top flaps, for example upon cartons having no tuck flaps and having their end or top flaps glued, in which case my closing devices press the glued flaps against the carton and hold them there while the glue or cement sets. Also, while the printing roller is not shown in connection with the platform chain embodiment illustrated in Figures 5 to 7 it is to be understood that the printer can be combined therewith in the same manner as shown in connection with the embodiments of Figures 8 to 12.

The invention may be embodied in other specific forms without departing from the spirit or essential characteristics thereof. The present embodiments are therefore to be considered in all respects as illustrative and not restrictive, the scope of the invention being indicated by the appended claims rather than by the foregoing description, and all changes which come within the meaning and range of equivalency of the claims are therefore intended to be embraced therein.

What is claimed and desired to be secured by United States Letters Patent is:

1. In a cartoning machine, a base; a transport for continuously moving a carton along said base while it is loaded, stationary means for partially closing the end flaps of the cartons by frictional engagement therewith, said stationary means producing a slight misalignment of the end flaps relative to the cartons; and means movable in the direction of movement of the cartons and operable by frictional engagement to complete the closing of the carton end flaps and simultaneously correct any deformation of the cartons resulting from the frictional engagement with said stationary means.

2. In a cartoning machine, a base; a transport for continuously moving cartons along said base while their end flaps are partially closed; movable means mounted on said base adjacent the path of the ends of the cartons and frictionally engageable with the end flaps of the cartons to close them; and means operative to drive said movable means in the direction of movement of the cartons at speed greater than that of said transport whereby said closing means exerts a wiping action on the carton end flaps in the direction of their movement.

3. In a cartoning machine; a base; a transport for continuously moving a carton along said base with its end flaps extending in opposite directions transversely of said base; stationary means on opposite sides of said transport for creasing the tuck flaps and folding the end flaps partially over the ends of the cartons while partially inserting the tuck flaps; movable final end flap closing means mounted on said base on opposite

sides of said transport in the path of the partially closed end flaps engageable with the end flaps to close them; and means operative to drive said final closing means in the direction of movement of the cartons at a speed greater than that of said transport whereby said closing means exerts a wiping action on the carton end flaps in the direction of their movement to correct any deformation of said cartons or end flaps caused by said stationary creasing and folding means.

4. In the machine described in claim 3, printing means arranged adjacent the path of movement of the carton end flaps following said final closing devices and operable to print upon the end flaps of the continuously moving cartons.

5. In the machine described in claim 4, said printing means comprising rotating type carrying elements; and means for driving said type carrying elements at the same speed as the moving cartons.

6. In the machine described in claim 3, means adjacent said final closing means for holding the end flaps in final closed position; and printing means cooperating with said flap holding means and operable to print upon the closed end flaps of the continuously moving cartons.

7. In the machine described in claim 3, a stationary vertical plate adjacent said final closing means and paralleling the direction of carton movement, for holding the end flaps in final closed position, said plate being provided with a transverse opening therethrough; printing means comprising rotating type carrying elements operable to project through said opening to print upon the closed carton end flaps; and means for driving said type elements at the same speed as the moving cartons.

8. In the machine described in claim 3, said final closing means situated on opposite sides of said transport being directly laterally opposite to each other to prevent lateral shifting of the cartons during the final closing operation upon their end flaps.

9. In a cartoning machine, a base; a transport for continuously moving a carton along said base while it is loaded and its end flaps partially closed; final closing means on said machine engageable with the partially closed flaps and operable to close them fully; means adjacent said final closing means for holding the flaps fully closed; and printing means cooperating with said flap holding means and operable to print upon the closed end flaps of the continuously moving cartons.

10. In the machine described in claim 9, means operative to drive said final closing means in the direction of movement of the cartons at a speed greater than that of the transport, whereby said final closing means exerts a wiping action on the carton end flaps in the direction of their movement to correct any deformation of said cartons caused by previous operations thereon.

11. In the machine described in claim 9, said printing means comprising a movable type carrying element; and means for driving said element at the same speed and in the same direction as the moving cartons while the impression is being made.

12. In the machine described in claim 9, means operative to drive said final closing means in the direction of movement of the cartons at a speed greater than that of the transport, whereby said final closing means exerts a wiping action on the carton end flaps in the direction of their movement; said printing means comprising a movable

type carrying element; and means for driving said element at the same speed and in the same direction as the moving cartons while the impression is being made.

13. In a cartoning machine, a base; a transport for continuously moving a carton along said base, stationary end flap closing means beside said transport for partially closing the end flaps and inserting the tuck flaps; movable final closing means mounted on said base adjacent the path of the end of the carton and engageable with the carton end flap to close it, comprising an element movable in a path converging with the path of the end of the carton; and means for driving said element along said path at a speed faster than that of said transport so that any misalignment of the carton end flaps produced by the frictional engagement between the stationary closing means and the carton end flaps is eliminated by the wiping action of the final closing means on the carton end flaps.

14. In the machine described in claim 13, said final closing means comprising a rotatably mounted drum and said driving means being operable to drive said drum so that its peripheral speed is greater than the linear speed of said transport.

15. In the machine described in claim 13, said final closing means comprising an endless element; means supporting one run of said element for movement in a path coplanar with the carton and converging with the path of the end of the carton; and means for driving said element at a speed greater than that of said transport.

16. In the machine described in claim 13, said final closing means comprising an endless chain; means supporting one run of said chain for movement in a path converging with the path of the end of the carton, said chain having elements attached thereto for presenting a smooth surface towards the carton, and said driving means being operable to drive said chain at a speed greater than that of said transport.

17. In the machine described in claim 13, said final closing means comprising a rotatably mounted drum having a friction providing peripheral surface and said driving means being operable to drive said drum so that its peripheral speed is greater than the linear speed of said transport.

18. In a cartoning machine, a base; a transport for continuously moving a carton along said base while it is loaded and its end flaps partially closed; drive means for said transport; final end flap closing means mounted on said base and movable in a path converging with the path of the end of the carton, comprising a drum mounted for rotation about an axis perpendicular to the plane of movement of the carton and positioned for frictional engagement with an end flap thereof; and means connected to said drive means for driving said drum with a peripheral speed greater than that of said transport.

19. In a cartoning machine, a base; a transport for continuously moving a carton along said base; drive means for said transport; closing means mounted on said base and movable in a path having a portion converging with the path of movement of the end of the carton, comprising an endless chain having face plates arranged perpendicular to the path of movement of the end of the carton along said converging path; and means for driving said chain at a speed greater than that of said transport.

20. In a cartoning machine, a base; a trans-

port for continuously moving a carton along said base while it is loaded and its end flaps partially closed; drive means for said transport; final end flap closing means mounted on said base and movable in a path converging with the path of the end of the carton comprising at least a pair of drums mounted for rotation about spaced axes perpendicular to the plane of movement of the carton in positions for frictional engagement with the end flaps thereof; means connected to said transport drive means for driving said drums at peripheral speeds greater than that of said transport; mounting means for mounting said drums on said base, said mounting means being constructed and arranged to adjust the location of each of said drum axes transversely of said base in accordance with the size of the carton.

21. In the machine described in claim 20, a rotatable printing drum mounted on said mounting means in the path of the carton end follow-

5

ing said closing means, for printing upon the closed end of the carton; and means connected to said transport drive means for driving said printing drum at a peripheral speed equal to that of said transport.

JOHN F. CURRIVAN.
